STAPLING MACHINE

Werner Schafroth, P.O. Box 247, Herrin, Ill.

Filed Jan. 24, 1963, Ser. No. 73,303

Term of patent 14 years

(Cl. D74—1)

FIG. 1 is a side elevational view of a stapling machine showing my new design,

FIG. 2 is a front elevational view thereof,

FIG. 3 is a top plan view thereof,

FIG. 4 is a rear elevational view thereof, and

FIG. 5 is a perspective view of the side opposite to that of FIG. 1.

The essential features of my design reside in the portions shown in solid lines.

I claim:

The ornamental design for a stapling machine, substantially as shown and described.
